UNITED STATES PATENT OFFICE.

EMMONS D. GUILD, OF ATTLEBOROUGH, MASSACHUSETTS.

DESIGN FOR A BOX-PLATE FOR CUFF-BUTTONS.

SPECIFICATION forming part of Design No. 25,092, dated January 28, 1896.

Application filed November 22, 1895. Serial No. 569,864. Term of patent 14 years.

To all whom it may concern:

Be it known that I, EMMONS D. GUILD, of Attleborough, in the county of Bristol and State of Massachusetts, have invented and produced a new and original Design for Box-Plates for Cuff-Buttons, of which the following is a specification, reference being had to the accompanying drawings, forming part thereof.

Figure 1 represents a plan view of a box-plate, illustrating my design. Fig. 2 represents a vertical cross-sectional view of the plate.

The leading feature of my design consists in the raised oblong portion with the open center. The outline of the plate corresponds

in general lines to that of the button. Part of this outline edge is curved downward and inward, as at 5 to 6. Within the outline formed by the curved portion from 5 to 6 is the surface 7, above which the rectangular raised portion 8 extends. At the back of this raised portion is the recess 9 and the surface of the raised portion has the opening 10.

What I claim is—

The design for a box-plate for cuff-buttons as herein shown and described.

EMMONS D. GUILD.
